LINT REMOVER MEANS FOR DRIERS

Joseph O. Huebsch, Fox Point, Wis., assignor to The American Laundry Machinery Company, Norwood, Ohio, a corporation of Ohio

Application May 18, 1955, Serial No. 509,363

5 Claims. (Cl. 34—82)

The invention relates to driers and more particularly to laundry or clothes driers of the rotating tumbler type.

The object of the invention is to provide a lint trap of simple construction located in the air circulating system of the drier adjacent the circulating fan for collecting lint and from which the lint may be readily removed by a reciprocating scraper and dropped into a receptacle below the trap and which receptacle may readily be removed from the machine, the lint trap itself being also preferably capable of removal as a unit from the drier.

This application is a continuation in part of my application, now abandoned, Serial No. 466,091, filed November 1, 1954, for Lint Remover Means for Driers, and is an improvement over said application in that the reciprocating scraper is made in two parts which act over the major area of the lint trap to scrape off the lint therefrom and with the aid of gravity dislodge the lint from the bottom portion of the trap.

The invention further consists in the several features hereinafter set forth and more particularly defined by claims at the conclusion hereof.

In the drawings:

Fig. 1 is a front elevation view of a drier embodying the invention;

Fig. 2 is a side elevation view of the drier, parts being broken away and parts being shown in section;

Fig. 3 is an enlarged end view of the lint removing apparatus, parts being broken away and parts being shown in section;

Fig. 4 is a detailed vertical sectional view taken on the broken line 4—4 of Fig. 3.

While the lint trap hereafter described may be used in the circulatory system of any suitable drier for laundry, garments, and textile materials, I have shown it associated with a drier of the rotating tumbler type.

Referring to Figs. 1 and 2, the drier includes a housing *S* having an air heater section *H*, a tumbler section *T*, and a lower section more particularly described.

The tumbler section *T* has a perforated drying tumbler or drum *6* mounted in it and supported at its rear end on a shaft *7* journaled in the housing and carrying a sprocket *8* connected by a suitably tensioned chain *C* with a sprocket *9* on a lay shaft *10* which carries a large pulley *11* connected by a belt *12* to a small pulley *13* on the shaft *S* of an electric drive motor *M*. The drum *6* is open at its front end and access thereto is had through an opening in the housing section *T* normally closed by a door *14* pivotally hinged at *15* on the housing.

The lower section of the housing includes a space *16* and a housing *17* for an exhaust fan *18* which is mounted on the outer end of the motor shaft *13*, the housing *17* having an inlet *19* communicating with the space *16* and an outlet *20*.

Referring to Figs. 3 and 4, within the space *16* an angled bracket member *21* has its legs suitably secured as by spot welding, to the front side of the housing *17*. A bar *22* is secured intermediate its ends to the legs of

2

the bracket *21* where they join each other, said bar providing supporting arms with downwardly inclined ends *23*.

A lint trap is formed of a cylinder *24* of perforated sheet metal or screening, a front closed end cap *25*, and a rear angle metal ring *26*, one of whose flanges is adapted to abut the front side of the housing *17* when the trap is positioned within the space and held up at its front end by engagement of the ends *23* of the bar *22* with the inner wall of the upper portion of the cylinder *24*. The end cap *25* is provided with a depression *27* and a cross bar *28* extending over the same to provide a handle whereby the trap may be moved to its operating position or removed therefrom.

With the above construction, air heated in the heater section *H* passes down into the drum section and then into the space *16* and is sucked by the fan *18* through the openings of the screen *24* and through the inlet *19* and then exhausted through the outlet *20* so that any lint from the clothes or other materials in the drum *6* carried along by the air will be caught on the outer surface of the cylinder *24*.

From time to time, the lint accumulating on the screen *24* may be removed by a reciprocating scraper preferably formed as a pair of arcuate blade members *29* that are pivotally mounted at their upper ends on the hooked end *30* of a rod *31* that is slidably mounted on a guide bracket *32* in the housing *5* and projects beyond the exterior thereof and carries a handle or knob *33*. Each blade member *29* has a portion *34* which rides or is closely spaced from the periphery of the screen cylinder *24* and a laterally flared lower end *35* which acts as a cam surface to move the blade away from or to clear the cylinder when the same is inserted in position. A bracket member *36* has a channelled end *37* mounted on the hooked end *30* and extending over the pivoted end portions of the blade members *29* and has a flared front end portion *38* to aid in guiding the cylinder to its operative position. The bracket member *36* also acts as a stop engageable with the outer ends *39* of the blade members to limit their inward swinging movement so that they can be pushed laterally to a position over the cylinder *24* by the cam actions of the ends *35* when the cylinder is moved into its operative position. The blades *29* under the action of gravity are free to contact the cylinder *24*.

With this construction the operator, grasping the knob *33*, may move the rod *31* forwardly and backwardly and thus similarly move the scraper blades *29* over the screen *24* to remove accumulated lint therefrom which is free to drop into a drawer or receptacle *40* having a handle *41* and slidably mounted and suitably guided in the bottom portion of the space *16* and movable outwardly of the front side of the housing. Since the blades *29* act upon about two-thirds of the area of the cylinder and extend beyond the center line of the cylinder, only the lower portion of the drum or cylinder *24* is not directly acted upon by the blades, but since collected lint tends to mat itself on the cylinder, it has been found that the loosening of this mat from the major portion of the cylinder also acts to loosen that part not directly engaged by the blades, and that gravity acting on this loosened mat will act to remove the lint from the bottom portion of the drum. The lint can be removed from the trap once or twice a day, and the accumulated lint removed from the drawer *40* once a week.

The housing *7* also has a removable front panel *41* closing an opening *42* in line with that part of the space *16* enclosing the lint trap so that this trap may also be removed from the housing for cleaning purposes, if necessary. The front panel *41* carries a transversely disposed handle *43* which projects at its end beyond the panel and acts as a bumper to prevent laundry trucks marring the housing. Panel *41* has inwardly extending

spaced slotted angle fittings 44 which engage over studs 45 mounted in frame parts of the housing as indicated in Fig. 4.

I desire it to be understood that this invention is not to be limited to any particular form or arrangement of parts except in so far as such limitations are included in the claims.

What I claim as my invention is:

1. In a drier having a housing provided with a drying space and an exhaust fan housing provided with an inlet communicating with said space, the combination of a foraminous lint collecting cylinder mounted in said space at the inlet to said housing, a scraper comprising a pair of gravity actuated arcuate blade members pivotally connected together at one of their ends adjacent the upper end of the cylinder and slidably movable over the major portion of the area of the cylinder, and means operable from outside said first named housing and forming a pivotal support for said blades to move said blade members forward and back relative to said cylinder.

2. In a drier having a housing provided with a drying space and an exhaust fan housing provided with an inlet communicating with said space, the combination of a foraminous lint collecting cylinder mounted in a substantially horizontally disposed position in said space at the inlet to said housing, a rod slidably mounted above said cylinder and extending lengthwise thereof and having an exteriorly disposed operating connection, a pair of gravity actuated arcuate scraper blades engageable with the cylinder throughout the major portion of its cross sectional area and pivotally suspended at their upper ends from said rod for movement therewith lengthwise of the cylinder.

3. In a drier having a housing provided with a drying space and an exhaust fan housing provided with an inlet communicating with said space, the combination of a foraminous lint collecting cylinder mounted in said space at the inlet to said housing, a rod slidably mounted above said cylinder and having an exteriorly disposed operating connection and an inner hooked end, a pair of scraper

blades pivotally mounted at their upper ends on the hooked end of said rod and movable therewith lengthwise of the cylinder to remove lint therefrom.

4. In a drier having a housing provided with a drying space and an exhaust fan housing provided with an inlet communicating with said space, the combination of a foraminous lint collecting cylinder detachably mounted in said space at the inlet to said fan housing, an opening in said housing adjacent said cylinder to permit removal of said cylinder therefrom, a removable panel covering said opening, a scraper blade slidably movable over a portion of said cylinder, a lint collecting receptacle below said cylinder and said panel and removable from the bottom portion of said space, and means operable from outside said first named housing to move said blade forward and back relative to said cylinder.

5. In a drier having a housing provided with a drying space and an exhaust fan housing provided with an inlet communicating with said space, the combination of a foraminous lint collecting cylinder mounted in said space at the inlet to said fan housing, a scraper comprising blade members pivotally connected together at one of their ends adjacent the upper end of the cylinder and slideably movable over the major portion of the area of the cylinder, each blade having a laterally diverging lower end forming a cam surface cooperating with the cylinder to move the blade laterally during the replacement of the cylinder, and means operable from outside said first named housing to move said blade members forward and back relative to said cylinder.
